UNITED STATES PATENT OFFICE

134,298

DESIGN FOR A DESK

James F. Eppenstein, Chicago, Ill.

Application September 28, 1942, Serial No. 108,347

Term of patent 7 years

To all whom it may concern:

Be it known that I, James F. Eppenstein, a citizen of the United States, residing at Chicago, in the county of Cook and State of Illinois, have invented a new, original, and ornamental Design for a Desk, of which the following is a specification, reference being had to the accompanying drawing, forming part thereof, wherein—

Figure 1 is a perspective view, looking toward one end and the working side of a desk, showing my new design; and

I claim:

The ornamental design for a desk, as shown.
JAMES F. EPPENSTEIN.
